DESIGN FOR A KEY HOLDER

Godfrey L. Dreher, Seattle, Wash.

Application March 17, 1947, Serial No. 137,676

Term of patent 7 years

(Cl. D87—3)

To all whom it may concern:

Be it known that I, Godfrey L. Dreher, a citizen of the United States of America, residing at Seattle, King County, Washington, U. S. A., have invented a new, original, and ornamental Design for Key Holders, of which the following is a specification, reference being had to the accompanying drawing, forming part thereof.

Fig. 1 is an enlarged perspective view of a key holder, showing my new design.

Fig. 2 is a side view of the key holder.

Fig. 3 is a plan view and Fig. 4 an end elevation of the same.

I claim:

The ornamental design for a key holder, as shown.

GODFREY L. DREHER.
